UNITED STATES PATENT OFFICE.

MERRILL H. TERRY, OF COLUMBUS, OHIO.

FUSE PLUG.

Application filed October 21, 1926. Serial No. 143,255.

This invention relates to improvements in fuse plugs of the type embodying a removable or replaceable fuse element which, when destroyed by an abnormal condition in an associated electric circuit, may be readily removed from the body of the plug and a new element substituted therefor in a simple and easily accomplished manner.

An object in the invention resides in the provision of a fuse plug of the character specified wherein the permanent body of the plug has the outer end thereof provided with an axially disposed socket in which is provided spaced resilient contact members, the said socket being adapted to receive a removable cartridge which carries a fusible element or strip, the arrangement being such that when the cartridge occupies an operative position within the socket, the fusible element thereof is resiliently engaged by the contact members so as to provide an effective electrical and mechanical connection between said members and the fusible element of the cartridge.

Another object resides in forming the cartridge to include a substantial transparent closure by which the condition of the fusible element or strip may be observed by an external inspection, the closure comprising an integral part of the cartridge assembly and is removable with said fusible element in an unitary manner.

Another object resides in the provision of the fuse plug wherein the cartridge unit is removable from the body of the plug from the front or outer end of the latter and without necessitating the removal of the plug body from an associated electric socket.

With these and other objects in view, which will appear as the description proceeds, the invention consists in the novel feature of construction, combination of elements and arrangement of parts hereinafter fully described and particularly pointed out in the appended claims.

In the accompanying drawings, which show an embodiment of the invention:

Fig. 1 is a vertical sectional view taken thru the plug.

Fig. 2 is a top plan view thereof.

Fig. 3 is a detail perspective view of the removable cartridge unit of the plug.

Referring more particularly to the drawing, the numeral 1 designates the body of the fuse plug. This body is preferably of one piece construction and is formed from por-

celain, composition or other insulating material. The body includes the usual enlarged central outer portion 2 externally knurled or roughened as at 3 to permit of its convenient handling. The inner or lower part of the body is reduced in diameter and is formed to include a threaded metallic sleeve 4, permanently held in place on said body. In this instance the body 1 has the outer end provided with an axially disposed socket 5 which extends well into the body of the plug. Positioned within said socket is a pair of spaced resilient contact arms 6 and 7, which are disposed contiguous to side walls of the socket. The arm 6 terminates in a downwardly and obliquely extending portion 8 which passes thru an angular slot provided in the body 1 and extends between the outer surface of said body and the socket. The downwardly extending portion 8 of said arm terminates in a curved or corrugated portion 9, which, in practice, is confined between sleeve 4 and adjacent outer wall of body 1, so as to provide a secure mechanical mounting for said arm 80 and a good electrical contact with the sleeve 4. The arm 7, which is spaced from the arm 6, includes an elongated shank portion 10, which in this instance passes axially thru the inner or lower part of the body 1, the extreme lower end of the shank being provided with a head 11 arranged exteriorly in a central position upon the lower or inner end of said body. The shank 10 is bent to extend parallel to the lower or inner wall of the socket 5, and is then bent perpendicularly to provide the arm 7 proper. The arms 6 and 7 are spaced sufficiently from the adjacent walls of the socket 5 to permit of their relative spreading when they are resiliently forced apart.

The construction of the plug so far described constitutes the permanent part thereof, and in association therewith the invention provides a removable or replaceable cartridge unit which is designed in its entirety by the numeral 12. This unit is receivable in a conveniently removable manner within the socket 5 and the construction of said unit is such that the same may be renewed from time to time with but minimum expense. In the embodiment of the invention herein described the said unit consists of a shell 13 of insulating material having the outer rim thereof provided with a metallic reinforcing ring 14, adapted for the reception and permanent connection of a transparent closure disc 15, which

is preferably formed from mica or some other suitable semi-transparent material. The shell is slotted at its inner end as at 15' to receive guide ribs 16 formed with the walls of 5 the socket 5, the construction serving to insure the positioning of the removable cartridge in a predetermined manner within the socket.

The lower or inner end of the shell 13 accommodates the U shaped ends 18 of a fusible contact strip or element 19. It will be observed that the manner of mounting the strip 10 in connection with the shell is such as to enable the ends 18 to extend substantially parallel to the arms 6 and 7, which will be engaged by the contact strip and resiliently forced apart to a slight extent, enabling said 15 arms to exercise resilient pressure on the arms 18 of the contact strip to provide: first, 20 a good electrical connection between said arms and the contact strip and, second, a means for mechanically retaining the cartridge unit in its applied position within the 25 socket. Around the outer end of the socket 5, there is provided in the body 1 an annular seat 20 which receives the bead 14 of said cartridge and limits the inward movement thereof. One or more notches 21 may be formed in the body 1 adjacent the seat 20 to 30 permit of the insertion of a tool or the like beneath the bead 14 and facilitate the removal of cartridge unit from the socket.

In view of the foregoing, it will be seen that in the event the fusible strip 19 is destroyed by an abnormal condition or over 35 load in an associated electric circuit, the cartridge unit may be readily removed from the body by outward sliding movement and a new unit inserted in the body in place thereof. It 40 will be observed that by forming the socket 5 at the outer end of said body this substitution or replacement can be accomplished without necessitating the entire removal of the plug from its associated socket. In practice, it is necessary merely to rotate the plug 45 in its socket so that the central electrode of the plug is out of engagement with the one of said socket and then the cartridge replacement may readily and safely be made.

50 Another important feature of the invention resides in the mounting the transparent disc 15 in the removable unit in such relation that the condition of strip 19 may be readily determined from an exterior inspection so 55 that when the fuse plugs are mounted in groups, the defective plug may be readily ascertained at a glance.

I do not desire to limit my invention to the 60 precise details of construction and arrangement as herein set forth as it is obvious that various modifications may be made therein without departing from the essential features

of my invention as defined in the appended claims.

What is claimed is:

1. A fuse plug comprising a body having one end thereof formed with an axially disposed socket, spaced resilient contact members mounted in connection with said body and extending in the inner part of said socket, 65 a removable shell formed to occupy said socket, a fusible contact strip carried by inner part of said shell and adapted for frictional engagement with said contact members, a substantially transparent closure carried by outer end of said shell and guide means for retaining said shell in a predetermined position within said socket. 70 75

2. A fuse plug comprising a body having a socket provided in one end thereof, spaced 80 contact members carried by said body and arranged adjacent to the inner end of said socket, a shell of insulating material formed to removably occupy said socket, a fuse strip carried by the inner part of said shell and 85 adapted for frictional engagement with said contact members, said strip being disposed transversely of said socket, and means formed with said body and shell for guiding the latter into a predetermined position within said 90 shell. 95

3. A fuse plug comprising a body having an axially disposed cylindrical bore formed in one end thereof, a pair of spaced contact members carried by said body and having 100 portions thereof extending vertically along the inner walls of said bore and arranged adjacent the inner end thereof, a cylindrical shell of insulating material formed to removably occupy said bore, a fuse strip carried by the inner part of said shell and disposed 105 transversely thereof, said fuse strip having portions thereof extending vertically along the outer walls of said shell and arranged to frictionally engage with the vertical portions of said contact members, a transparent closure carried by the outer end of said bore, and means formed with the body and shell for retaining the latter in a predetermined position within said bore. 110

4. A fuse plug comprising a body having an open ended bore axially disposed therein, a pair of spaced contact members carried by said body and extending in the inner part of said bore, a removable shell formed to occupy 115 said bore, a fusible strip carried by the inner part of said shell and adapted for frictional engagement with said contact members, a substantially transparent closure carried by the outer end of said shell, and means formed 120 with the outer end of said shell for facilitating its removal from said bore.

In testimony whereof I affix my signature.
MERRILL H. TERRY.
